UNITED STATES PATENT OFFICE.

WINTHROP K. HOWE, OF ROCHESTER, NEW YORK, ASSIGNOR TO GENERAL RAILWAY SIGNAL COMPANY, OF ROCHESTER, NEW YORK.

SKATE MACHINE.

Application filed November 20, 1925. Serial No. 70,337.

This invention relates to an emergency stop device for stopping free running railway cars, and more particularly to means for placing such stop device into and out of its 5 active stopping position.

In connection with gravity or hump classification yards, it is desirable to employ a device, commonly called a skate, for stopping cars. The skate is placed on the track rail, 10 and the wheel of the car rides on to this skate, carrying it along with the car and tending to stop the car by sliding the first pair of wheels and also by virtue of the friction between the skate and the rail.

15 While these skates are ordinarily placed on the track by hand, it has been proposed to provide an operating mechanism, conveniently termed a skate machine, which will act automatically, under manual control from 20 a distant point, to place the skate on a track rail in its operative position. The present invention relates to such a skate machine.

In accordance with the present invention, 25 it is proposed to provide a skate machine, power-operated and manually controllable from a distant point, in which the skate is supported and carried in such a way by the machine that it can be placed on the rail in its active position, or removed from the rail, 30 so that the skate machine may be tested whenever desired. Also, it is proposed to provide an operating connection to the skate in such a way that the skate may be engaged by a car wheel and carried away from the 35 skate machine, even though the skate may have been in its operated position and without damage to it. More specifically, it is proposed to provide an operative, but detachable, connection between the skate and a 40 power-operated holder, this connection in the specific form illustrated being made in the form of a keyed or tapered dove-tailed construction.

45 Other objects, purposes and characteristic features of construction will be pointed out hereinafter and will in part be apparent from the drawings.

In describing the invention in detail, reference will be made to the accompanying 50 drawings in which:

Fig. 1 is a plan view of an embodiment of the present invention, in which the motive power mechanism casing is partly broken away and in which the skate holder is shown

with a skate therein and in its inactive position;

Fig. 2 is an end view of the skate machine taken on the line 2—2 of Fig. 1 as viewed in the direction of the arrows.

Fig. 3 is an end elevation the same as that shown in Fig. 2, except that the skate holder and skate are shown in their active position; and

Fig. 4 is a side elevation of the skate placing member in its inactive position, particularly illustrating the tapered key, wedge or tenon which is adapted to engage a correspondingly shaped slot in the skate.

Referring to Fig. 1 the left hand track rail 1 of a classification track is shown carried by the usual ties 2, the direction of traffic being from left to right as indicated by the arrow. To the rail 1 is clamped a base member 3 by hook bolts 4, this base member being shaped to form a bearing block having a bearing substantially parallel to the rail, which block pivotally supports the skate placing member 5 through the medium of a short shaft 6, thus permitting the member 5 to be swung about a pivot from its inactive position shown in Fig. 2 to its active position shown in Fig. 3. This member 5 has a tapered key or tenon projecting from the top thereof which fans out so as to constitute one member of a so called, tapered dove-tailed connection, the shape of this key or tenon and slot or mortise being readily apparent from Figs. 3 and 4 of the drawings, the normal direction of traffic in Fig. 4 being from right to left as indicated by the arrow. The 70

skate S which is somewhat wider than the top face of the rail 1 has downwardly projecting flanges 10 and 11 which are adapted to engage the side of the rail, so as to prevent the skate from leaving the rail when the wheel of a car rides onto the same and causes it to slide along the rail with the wheel. The flange 10 is hollowed out as shown at 12 to afford a pocket for the flange of the car wheel, this hollowed out portion or groove 12 being curved upward substantially at the curvature of the car wheel. At the front end of the skate are provided projecting extensions, between which is pivotally supported a roller 14. This roller 14 is so positioned with respect to the lower face of the skate S that it is out of contact with the top surface of the rail while riding on a rail,

this roller being provided to aid the skate in riding from one rail to the next past a joint in the track. This skate S has a rather wide lug 15 extending therefrom in the bottom side of which is contained a tapered slot or mortise, which widens out inwardly to accommodate the tapered key or tenon projecting from the skate placing member 5 heretofore described, the shape of this key and the counter part thereof being readily understood from the illustrations shown in Figs. 3 and 4.

By looking in Figs. 2 and 3 it readily appears that the turning of shaft 6 causes the 15 skate placing member 5, and the skate detachably connected thereto, to be moved from one position to the other. And in order to avoid the motive power mechanism for operating this skate being damaged in the event 20 the skate should fail to disengage from its holder when a car rides thereon and carries the skate with it, or in the event the car truck is entirely derailed when it strikes the skate, the motive power mechanism is preferably 25 located some distance from the skate, and preferably toward the left, that is to the rear of the skate placing member as shown in Fig. 1. In accordance with the present invention the shaft 6 is connected to a socket 30 member 20 by a universal joint 21 constructed in the usual way, this socket member 20 being provided with a square hole into which the square shaft 22 snugly fits, the other end of this squared shaft being connected by the 35 universal joint 23 to the operating shaft 24 of the motive power mechanism contained in the casing 25. This shaft 24 having contained thereon a yoke 27 forming a pair of lever arms between which is pivoted an operating 40 bar 28 by a pin 29. It thus readily appears that if the bar 28 is operated back and forth that the skate S is operated from its normal position, in which it lies on the 45 stop or rest plate 30, to its active position on the rail and back again.

If now, the skate is moved to its active position, as shown in Fig. 3, the passage of a car moving from left to right causes its 50 left hand front wheel to ride on the skate S thus causing the skate to slide along on the rail 1 and in so doing disengage from the skate placing member 5, and due to the additional friction injected, by the sliding of the first wheels and axle, causes the car to be brought to a stop. In the event, however, 55 that the passage of a car in carrying the skate with it causes binding engagement between the skate and the member 5 and carries the member 5 together with the support 60 3 with it, no damage is likely to be done to the motive power mechanism, by reason of the sliding engagement between the skate member 20 and the square shaft 22. Also, since the skate placing member is located to 65 ward the right of the motive power mecha-

nism the apparatus carried by the car wheels is carried away from and not toward the motive power mechanism.

In order to simplify the drawings and description of the particular form of the invention illustrated no specific means for operating the operating bar 28 has been shown. It is, however, desired to be understood that the motive power casing 25 may contain suitable electrically operated means whereby the 70 bar 28 may be reciprocated, or may contain suitable pneumatically operated or fluid pressure operated mechanism for operating the bar 28 in one direction or the other as conditions require. Also, that the motive 75 power mechanism in casing 25 may be controlled from the operator's tower at some distance from the skate machine. The tapered key or dove tailed detachable connection between the skate placing member 5 and the skate S is preferably such as to constitute a rather loose fitting connection, this in order to avoid binding between the member 5 and the skate S as the skate is dragged 80 off by a passing car. Also, it is desired to point out that the taper of the key is such as to materially lessen the danger of binding 85 between these two devices upon endwise movement of the skate S.

The particular embodiment of the invention illustrated and described thus permits the control mechanism as well as the operating mechanism, whether electrically or fluid pressure operated, to be tested at intervals 90 so as to detect the failure of any of the component parts constituting the skate placing 95 apparatus, and permits the skate to be returned to its inactive position after such testing.

Having thus shown and described a single embodiment of a skate machine which 100 permits a skate to be moved to and from its active position as conditions require, and which permits ready disengagement of the 105 skate from the skate placing mechanism when the skate is moved longitudinally on the track rail, it is desired to be understood that the particular arrangement shown and described has been illustrated for the purpose of facilitating the description of the 110 invention and not with the idea of illustrating the specific construction preferably employed in practicing the invention nor with the idea of illustrating the scope of the invention, and that various changes, modifications and adaptations may be made without departing from the scope of the invention 115 or the idea of means for carrying out such invention.

What I claim as new is:

1. In an emergency train stop device, the combination with a railway rail, of a support fixedly secured to said rail, a skate placing mechanism pivotally connected to said support having one element of a slid- 120

- able non-rotatable detachable connecting means associated therewith, a skate adapted to fit on the rail and skid the first wheels and axle of a passing car and having the 5 counter part portion of said slidable non-rotatable detachable connecting means associated therewith, and power operated means for operating said skate placing mechanism to move said skate from one to the other 10 of its active and inactive positions.
2. In an emergency train stop device, the combination with a railway rail, of a support fixedly secured to said rail, a skate placing mechanism pivotally connected to said support having one element of a slid- 15 able non-rotatable detachable connecting means associated therewith, a skate adapted to fit on the rail and skid the first wheels and axle of a passing car and having the 20 other element of said slidable non-rotatable detachable connecting means associated therewith, power operated mechanism adapted to be controlled from a remote point, and a shaft including a universal 25 joint for operatively connecting said power operated mechanism and said skate placing mechanism.
3. In an emergency train stop device, the combination with a railway rail, of a support fixedly secured to said rail, a skate placing mechanism pivotally connected to said support having one element of a slid- 30 able detachable connecting means associated therewith, a skate adapted to fit on the rail and skid the first wheels and axle of a passing car and having the other element of said 35 detachable connecting means associated therewith, power operated mechanism controllable from a distant point, and a shaft having a universal joint operatively connecting 40 said power operated mechanism to said skate placing mechanism by another slid- 45 able disengageable connection.
4. In an emergency train stop device, the combination with a railway rail, of a support fixedly secured to said rail, a skate placing mechanism pivotally connected to said support having one element of a slid- 50 able detachable connecting means associated therewith, a skate adapted to fit on the rail and skid the first wheels and axle of a passing car and having the other element of said 55 detachable connecting means associated therewith, power operated mechanism controllable from a distant point including a casing having a rockable shaft projecting therefrom, and another shaft connected to said rockable shaft by a universal joint, the free end of said second mentioned shaft being disengageably connected to said 60 skate placing mechanism.
5. In an emergency train stop device the combination with a railway rail, of a support fixedly connected to said rail, a shaft disposed substantially parallel to said rail 65 pivotally supported in said support, skate placing mechanism fixedly connected to said shaft and adapted to be moved to an active and an inactive position and having one element of a quick detachable slidable connection associated therewith, a skate having a portion thereof formed to constitute a counter part of said one element for detachably connecting the skate to said skate placing mechanism, and a power operated shaft 70 slidably detachably but operatively connected to said first mentioned shaft.
6. In an emergency train stop device, the combination with a railway rail, of a support fixedly secured to said rail, a skate placing mechanism pivotally connected to said support having one element of a slid- 75 able detachable connecting means associated therewith, a skate adapted to fit on the rail and skid the first wheels and axle of a passing car and having the other element of said 80 detachable connecting means associated therewith, power operated mechanism located directly in the rear of said skate placing mechanism for the direction of car 85 movement which said skate is adapted to retard, and a detachable operative connection for connecting said skate placing mechanism for operation by said power operated mechanism, whereby injury to said skate placing 90 mechanism due to a passing car is not apt to injure said power operated mechanism.

In testimony whereof I affix my signature.

WINTHROP K. HOWE.
